UNITED STATES PATENT OFFICE.

LEWIS M. PRATT, OF OKLAHOMA, OKLAHOMA.

BURGLAR-ALARM.

991,643.

Specification of Letters Patent. Patented May 9, 1911.

Application filed October 26, 1910. Serial No. 589,168.

To all whom it may concern:

Be it known that I, LEWIS M. PRATT, a citizen of the United States, residing at Oklahoma city, in the county of Oklahoma and State of Oklahoma, have invented a new and useful Burglar-Alarm, of which the following is a specification.

It is the object of the present invention to provide an improved burglar alarm of that type designed to be mounted upon a door frame and to be operated through the opening of the door.

The primary aim of the invention is to provide a device of this type extremely simple in its construction, readily set, and so compact as to be entirely out of the way when not in use.

A further feature of the invention resides in so constructing the device that it may be applied to a door frame in which the door opens to the right or to the left, the device embodying a trip finger which is of soft metal and may be bent to engage selectively with oppositely located shoulders which normally hold it and the hammer by which it is carried, in set position.

In the accompanying drawings, Figure 1 is a view in side elevation of the device applied to a door frame. Fig. 2 is a vertical longitudinal sectional view through the device. Fig. 3 is an end elevation thereof. Fig. 4 is a top plan view.

In the drawings, the device is illustrated as embodying a casing which is preferably of sheet metal and is open at its top and bottom, the side walls of the casing being indicated by the numeral 5 and one end wall being indicated by the numeral 6. The opposite end of the casing is closed by a cartridge holding member 7 preferably in the nature of a block of metal projecting at its upper end above the plane of the upper edges of the side walls 5 and formed in its said projecting end with a cartridge receiving opening 8 in which may be inserted an ordinary blank cartridge indicated by the reference character B in Fig. 2 of the drawings. Through the side walls of the casing and through the said blocks 7 are formed openings indicated by the numeral 9 and through these openings a securing screw 10 is to be passed for the purpose of attaching the device upon the door frame, the said door frame being indicated in Fig. 1 of the drawings by the reference character D and the door which is mounted to swing in the frame

being indicated by the reference character D'.

At its lower end, the cartridge holding block 7 is recessed as at 11 and seating pivotally in this recess is the lower end 12 of a hammer 13. This hammer 13 carries a firing pin 14 near its upper end which pin is so located as to strike the cap of the cartridge B when the hammer is forcibly swung from the position shown in Fig. 1 of the drawings to the position shown in Fig. 2 of the drawings. This swinging movement of the hammer in the direction of the cartridge holding block is accomplished through the medium of a leaf spring 15 which is seated at one end in a notch 16 formed in the hammer 13 and at its other end is engaged beneath a lug 17 formed at the lower end of a slot 18 in the end wall 6 of the casing. The slot 18 is wider at its upper end than near its lower end or in other words, its edges converge downwardly so that as a result, shoulders 19 are formed in the edges of the slot near its lower end. Rigidly carried by the hammer 13 is a finger 20 which projects in the general direction of the end wall 6 of the casing and is of sufficient length to project beyond said end wall and, when the hammer is in the position shown in Fig. 1 of the drawings, to project through the slot 18 and engage with one or the other of the shoulders 19. The finger 20 is preferably formed of some soft metal such for example as soft iron and may consequently be bent to the form shown in full lines in Fig. 4 of the drawings or to the form shown in dotted lines in the said figure. In the first instance, it will engage with the right hand one of the shoulders 19 in Fig. 3 of the drawing and in the latter instance with the left hand one of the said shoulders. It will at this point be readily understood that the finger is to be bent to one form or the other depending upon whether the device is to be applied to a door frame in which the door opens to the right or to the left, it being understood that the door in swinging to open position, engages the extremity of the finger 20 and shifts this finger laterally to such degree as to disengage it from the shoulder 19 with which it is engaged when in set position.

From an inspection of Fig. 1 of the drawings it will be observed that should the door D' be swung to open position, the extremity of the finger 20 would be engaged

and the said finger would then be disengaged from the shoulder 19 by which it is held in set position, and upon being released would swing upwardly together with 5 the hammer 13 by which it is carried. This movement of the hammer through the agency of the spring 15 will serve to bring the firing pin 14 forcibly into contact with the cap of the cartridge B and the said 10 cartridge will be exploded.

It will be understood of course that the device will be so applied upon the door frame that when the finger 20 is disengaged from the retaining shoulder 19, it 15 will swing up to position out of the way of the door in its further swinging movement.

What is claimed is:

1. In a device of the class described, a casing, a cartridge holding member at one 20 end of the casing, a hammer pivotally connected with the cartridge holding member and coöperating therewith, a spring interposed between the hammer and the opposite end wall of the casing, the said last mentioned end wall of the casing being formed 25

with a slot and the edges of the slot being formed each with a shoulder, and a finger rigidly carried by the hammer and arranged for movement in the slot and to be engaged selectively with the shoulders. 30

2. In a device of the class described, a casing, a cartridge holding member at one end of the casing, a hammer pivotally engaged with the cartridge holding member, the opposite end wall of the casing being 35 slotted and formed in the edges of its slot with opposed shoulders, a spring bearing against the hammer, and a finger rigidly carried by the hammer and arranged to work in said slot, the said finger being of material permitting of its being bent to engage with either one of said shoulders. 40

In testimony that I claim the foregoing as my own, I have hereto affixed my signature in the presence of two witnesses.

LEWIS M. PRATT.
